DAVENPORT BED.

APPLICATION FILED NOV. 25, 1905.

2 SHEETS—SHEET 2.

UNITED STATES PATENT OFFICE.

GEORGE A. MELLON, OF ST. LOUIS, MISSOURI.

DAVENPORT-BED.

No. 820,808.

Specification of Letters Patent.

Patented May 15, 1906.

Application filed November 25, 1905. Serial No. 288,998.

To all whom it may concern:

Be it known that I, GEORGE A. MELLON, a citizen of the United States, residing in the city of St. Louis, in the State of Missouri, have invented certain new and useful Improvements in Davenport-Beds, of which the following is a full, clear, and exact description, reference being had to the accompanying drawings, forming part of this specification.

My invention relates to that class of folding beds commonly known under the name of "davenports," and it has for its object to provide simple and efficient means for movably connecting the movable section of the bed to the stationary section during the unfolding and folding action.

It also has for its object to provide a simple and efficient bracing-fastener for securing the bed-rails to the posts; also, to provide means whereby a sheet or bedding is automatically stretched across the sections of the bed when they are unfolded and automatically return into a compact condition when the sections are folded; also, to provide means for covering the pads or mattresses of the bed-sections.

Figure I is an end elevation of my davenport-bed in the folded condition in which the parts are placed when the bed is to be used as a seat. Fig. II is a view similar to Fig. I, showing the movable or back section of the bed folded onto the stationary or seat section. Fig. III is an end view of the bed in the unfolded condition, in which it is used as a bed. Fig. IV is a rear view of one of the end portions of my bed, the bedding-receiving roller being shown partly in longitudinal section. Fig. V is a front elevation of one of the end posts of the bed.

A designates the stationary or seat section of my bed, and B the movable or back section. The stationary section A has end supporting-posts 1, that are united by end rails 2 and are tied together at their upper ends by horizontal head and foot members 3. Each of the posts 1 is provided with a hook 4. (See Figs. IV and V.)

5 6 designates side rails by which the pairs of end posts 1 are joined. These side rails each have secured to its ends a fastening member 7, by which the side rails are secured to the end posts. Each fastening member 7 has a central horizontally-disposed socket-arm 8, that is adapted to be fitted to a post-carried hook 4 for the purpose of attaching the side

10 rail to the adjacent post, and each fastening member has a pair of brace-arms 9, one of which is located above the socket-arm and the other below the socket-arm. These 60 brace-arms terminate in curved forks that fit against the end post to which the fastening member is secured and serve to brace said end post against lateral movement. The stationary member A of the bed has mounted 65 therein a pad or mattress A', which is supported by the end rails 2 and side rails 6.

The movable member B has main end bars 10 and supplemental end bars 11, the former being located adjacent to the back of the 70 member and the latter extending forwardly from the former at the edge of the section B which is uppermost when the section is in the position seen in Figs. I, IV, and V. The end bars 10 and 11 have suitably secured to them 75 a pad or mattress B'. Each main end bar 10 has fixed to it a stud 13. Each supplemental end bar 11 has extending from it a stud 14. The utility of these studs 13 and 14 will hereinafter be defined.

80 15 designates one of a pair of uprights secured to the end rails 2 and extending upwardly therefrom. These uprights are located at the forward side of the stationary rail-section A, preferably in proximity to the 85 end posts 1, that support the forward sides of said stationary section. Each upright 15 terminates at its upper end in a hook 16, which is curved downwardly from the front side of the upright, and a runway portion 17, 90 that extends rearwardly from said hook.

18 designates one of a pair of swinging arms having free ends 19 disposed at an angle to the main bodies of the arms. Each of these swinging arms is pivoted at 20 to an 95 upright 15 in order that the arm may be swung vertically with respect to said pivotal point. Each swinging arm is also pivoted at 21 to the adjacent main end bar 10 of the bed-section B, said last-named pivotal point 100 being located adjacent to one end of the end bar to which the swinging arm is attached, this point being lowermost with respect to the movable section when said movable section is in folded condition, as seen in Fig. I, 105 and outermost when the bed is in unfolded condition, as seen in Fig. III. The free ends 19 of the swinging arms which project beyond the pivotal points 21 are adapted to extend upwardly from said pivotal points 110 when the bed is folded, as seen in Fig. I, and while in this position said arm ends serve to

receive the engagement of the studs 13, carried by the movable-bed-section end bars 10, thereby preventing rearward movement of said section while it serves as a seat-back.

5 The free ends of the arms serve as movable bed-section-supporting legs when the bed is in the unfolded condition. (Seen in Fig. III.)

When my davenport-bed is to be changed from the condition in which it is seen in Figs.

- 10 I, IV, and V, in which it serves as a seat, to the unfolded condition, in which it is seen in Fig. III, in which it is serviceable as a bed, the parts are moved in the following manner: The movable section B is first grasped 15 by its upper portion and swung forwardly in the direction indicated by the arrow, Fig. I, during which action the lower portion of said section rides upon the top surface of the stationary section A, on which it rests, the 20 swinging arm 18 at this time rising sufficiently to permit the movement of the movable section. The movement of the movable section is continued until the side of said section previously facing forwardly is brought 25 to rest in a flat condition on the stationary section A. The parts of the bed will then be in the positions illustrated in Fig. II. When the parts are in this position, the studs 14, carried by the movable-section end bar 11, 30 rest upon the runway portions 17 of the uprights 15 and are located at the rear of the hooks 16 of said upright. The unfolding action is then completed by lifting the edge of the movable section farthest removed from 35 the hooks 16 and swinging the section forwardly in the direction indicated by the arrow, Fig. II, and during the movement of said section the swinging arms 18 swing therewith by pivoting on the pivot-points 20. 40 As the movable section is moved the studs 14 are carried forwardly until they seat in the hooks 16 to serve as pivotal members for the movable bed-section while it is being lowered into horizontal alinement with the stationary section A, as seen in Fig. III. Upon 45 the movable section being lowered into alinement with the stationary section the free ends 19 of the swinging arms 18 are brought to the floor and in this position serve as supporting-legs for the movable section.

50 22 designates one of a pair of bowed head and foot members secured to the swinging arms 18. These head and foot members are moved into the positions seen in Figs. I, II, 55 IV, and V when the bed is folded and at such time are of no utility. When the bed is unfolded, they form head and foot members for the movable bed-section, as seen in Fig. III.

55 23 designates a spring-controlled roller 60 that is rotatably supported in a manner similar to that in which window-shade rollers are supported by brackets 23', secured to two of the end posts of the bed at opposite ends thereof. This spring-roller has fixed thereto 65 one end of a sheet 24 or other bedding, which

is adapted to be wound onto the roller. The other end of the sheet or bedding is secured to the movable bed-section B at its edge which is outermost at the time that the bed is in unfolded condition. When the bed-section is in folded condition, the sheet or bedding extends downwardly in front of the movable bed-section, thence rearwardly beneath the lower edge of the section and onto the spring-roller, on which it is partially wound. When the bed is being unfolded by shifting the movable section in the manner described, the sheet or bedding is gradually drawn from the spring-roller across the stationary bed-section and finally lies flatly 8 across both of the bed-sections, as seen in Fig. III.

25 designates a wrapper-sheet that is applied to the movable section B of the bed so as to completely cover the side of said section which faces forwardly when the bed is in folded condition. The ends of this wrapper-sheet terminate at the back of said movable section, and they may have situated therein rods 26, as indicated in dotted lines Fig. IV.

27 denotes draw-springs connecting the ends of the wrapper-sheet and serving to hold said sheet stretched in a taut condition. The springs 27 are preferably of coiled form; but any other suitable form of springs may be utilized. The wrapper-sheet may serve not only to present a smooth surface at the front of the movable section, but as a means for holding the pad or mattress of said section securely to the frame of the section.

While I have shown and described the ends of the wrapper-sheet as united by the springs by which the sheet is held stretched, it is obvious that the same result might be accomplished by attaching springs to the ends of the sheet and to the bed-section frame or by securing one end of the sheet to said frame and connecting the other end to the frame by the springs. It is also obvious that while I have only shown and described the wrapper-sheet as applied to the movable bed-section, it may, if desired, be also applied to the stationary bed-section.

I claim—

1. In a folding bed, the combination with a stationary section and a folding section, of means whereby said folding section is movably connected to said stationary section, and means whereby said folding section is caused to pivot directly on said stationary section when being unfolded and folded, substantially as set forth.

2. In a folding bed, the combination with a stationary section and a folding section, of means whereby said folding section is movably connected to said stationary section, said sections being provided with pivot members unconnected to each other and arranged to engage and act in conjunction with each

- other to cause said folding section to pivot directly on said stationary section when being unfolded and folded, substantially as set forth.
5. 3. In a folding bed, the combination with a stationary section and a folding section, of means whereby said folding section is movably connected to said stationary section, a hook associated with one of said sections, and
- 10 a stud associated with the other section adapted to act in conjunction with said hook to cause said folding section to pivot on said stationary section when being unfolded and folded, substantially as set forth.
- 15 4. In a folding bed, the combination with a stationary section and a folding section, of means whereby said folding section is movably connected to said stationary section, a hook associated with said stationary section,
- 20 and a stud associated with said folding section; said stud and hook being arranged for engagement to cause said folding section to pivot on said stationary section when being unfolded and folded, substantially as set forth.
- 25 5. In a folding bed, the combination with a stationary section and a folding section, of means whereby said folding section is movably connected to said stationary section, a
- 30 stud carried by said folding section, and a hook and runway member supported by said stationary section and adapted to receive said stud, substantially as set forth.
- 35 6. In a folding bed, the combination with a stationary section and a folding section, of a single pair of swinging arms each having pivotal connection with said sections to unite them; said folding section being arranged to pivot directly on said stationary section
- when being unfolded and folded, substantially as set forth. 40
7. In a folding bed, the combination with a stationary seat-section and a folding back-section, each having a face portion; of means whereby said folding section is movably connected to said stationary section in a manner to permit of a forward-and-downward movement of said back-section so that it is first brought to rest in a horizontal position upon said stationary section with the face portions 45 of the members touching each other, and means for causing said back-section to pivot on said stationary section when the back-section is swung forwardly and downwardly from its position above the stationary section to a position in front of and in horizontal alignment with said stationary section, substantially as set forth. 50
8. In a folding bed, the combination with a stationary section and a folding section, of a swinging arm having pivotal connection with said sections to unite them and permit folding action of said folding section, a stud at the end of said folding section; said swinging arm being provided with a free end to receive the engagement of said stud, substantially as set forth. 55
9. In a folding bed, the combination of a stationary section and a folding section, of a swinging arm having pivotal connection with said sections to unite them, and a head or foot member carried by said swinging arm, substantially as set forth. 60
